(57) **CLAIM**

The ornamental design for a ring toss game, as shown and described.

DESCRIPTION

FIG. 1 is a perspective view of a ring toss game, showing my new design;

FIG. 2 is another perspective view thereof;

FIG. 3 is a front elevation view thereof;

FIG. 4 is a rear elevation view thereof;

FIG. 5 is a left side elevation view thereof, the right side elevation view being a mirror image of FIG. 5;

FIG. 6 is a top plan view thereof; and,

FIG. 7 is a bottom plan view thereof.

The broken lines in the figures depict portions of the ring toss game that form no part of the claimed design.

1 Claim, 7 Drawing Sheets
